DESIGN FOR A CHAIN FOR A WATCH BAND
OR SIMILAR ARTICLESalvatore Esposito and Dominic Vassalluzzo,
Philadelphia, Pa.

Application April 7, 1947, Serial No. 138,218

Term of patent 14 years

(Cl. D45—4)

To all whom it may concern:

Be it known that we, Salvatore Esposito and Dominic Vassalluzzo, citizens of the United States of America, residing at Philadelphia, in the county of Philadelphia and State of Pennsylvania, respectively have invented a new, original, and ornamental Design for a Chain for a Watch Band or Similar Article, of which the following is a specification, reference being had to the accompanying drawing forming a part thereof, wherein:

Figure 1 is a top plan view of a chain for a watch band or similar article, the links shown in full lines being continuous throughout the length of the chain as indicated by the broken lines; and

Figure 2 is an edge elevational view of the chain as shown in Fig. 1.

We claim:

The ornamental design for a chain for a watch band or similar article, as shown.

SALVATORE ESPOSITO.
DOMINIC VASSALLUZZO.
